UNITED STATES PATENT OFFICE.

WILLIAM REID, OF HAMILTON, SCOTLAND.

CONNECTION WITH APPARATUS FOR TIPPING WAGONS.

1,340,683.

Specification of Letters Patent.

Patented May 18, 1920.

Application filed October 21, 1919. Serial No. 332,350.

To all whom it may concern:

Be it known that I, WILLIAM REID, a subject of the King of Great Britain and Ireland, and a resident of Hamilton, Lanark, Scotland, have invented certain new and useful Improvements in Connection with Apparatus for Tipping Wagons, of which the following is the specification.

This invention relates to apparatus for tipping wagons, the apparatus being of the type in which there is provided a platform over which the wagon is run, this platform being mechanically raised at one end to tip the wagon, and means being provided to hold the wagon on the platform during this operation; and the invention has for its object to provide an improved and simple arrangement of the raising and lowering mechanism of such apparatus.

Apparatus made according to the invention comprises essentially a platform pivoted at one end adjacent to a hopper into which the contents of the wagon are to be discharged, a vertically movable hoisting beam pivoted at its upper end to the opposite end of the platform, a head on the beam capable of engaging with the rear axle of the wagon; a guiding rod (or rods) hinged at one end to the lower end of the beam, its other end being pivoted on a fixed center, a winding drum and a hoisting rope or chain passing therefrom over pulleys, the guiding rods causing the lower end of the beam to follow a prescribed path during the tipping operation. If desired, means may also be provided to counterbalance the weight of the platform and wagon.

The improved apparatus is shown on two accompanying sheets of explanatory drawings in which Figure 1, Sheet 1 is a plan, and Fig. 2 a vertical section, showing the improved apparatus in duplicate, one on either side of a hopper, so that if the end door of the wagon comes in the wrong direction for one tipper, it will be right for the other. Figs. 3 and 4, Sheet 2 are sectional elevations at right angles to each other, and to a considerably larger scale of the operating beam, while Fig. 5 is a horizontal section on the line A—B Fig. 4.

As shown on the drawings, there is provided a platform C consisting of side beams and connecting framing. This platform is hinged at its inner end to girders C¹ extending over a hopper C² into which the contents of the wagon C³ are to be tipped.

The platform extends between rails B (Fig. 4) over which the wagon to be tipped is run. Pivoted to the free end of the platform C, there is what may be termed a hoisting beam D¹, composed of side members braced together. The head of this beam has in it a groove D² capable of engaging the rear axle of the wagon, as hereinafter described. To the lower end of this beam D¹ there is pivoted one end of a pair of guiding rods G, the opposite ends of which are pivoted to the under side of the hopper C². A winding drum G¹ driven through gearing G³ from a prime mover G⁴, has secured to its opposite ends the two ends of a hoisting rope H. The rope passes down to and under pulleys H² on a spindle J turning in bearings provided for it in the lower end of the beam D¹, then up to and over pulleys J², 75 the spindle for which is carried in stationary bearings. From the pulleys last mentioned, the loop of the rope passes to and around a pulley K, the bearings for the spindle of which are carried in blocks K¹, 80 connected to a weight K² capable of sliding between fixed girders K³.

From extensions on the ends of the winding drum G¹ ropes pass over pulleys L to weights L¹ which counterbalance the weight 85 of the empty wagon and of the platform.

To tip a wagon C³ which has been run over either platform C, the winding drum G¹ is started in the appropriate direction to cause the hoisting rope H to apply lifting 90 strain to the pulleys H² on the lower end of the hoisting beam D¹ and consequently start to raise that beam. The groove D² in the head of the beam D¹ then immediately engages with the rear axle of the wagon, and 95 during the continued upward movement of the beam, its lower end follows the path prescribed by the travel of the guiding rods G and the upper end of the beam D¹ travels in the arc prescribed by the travel of the platform C. The continued upward travel of the beam D¹ raises the platform C on its pivot and carries the wagon C³ into the tipping position, the front axle of the wagon resting on the platform during this movement, and the wagon being held on the platform by the groove D² in the head on the beam D¹ engaging the rear axle of the wagon. The upward movement of the parts is facilitated by the weights L¹ counterbalancing the weight of the wagon and platform. 105 110

To lower the wagon C³, the direction of rotation of the winding drum G¹ is reversed so that the wagon, the platform, and hoisting beam all descend to their normal position, the weighted pulley K keeping the necessary tension on the hoisting rope H if this operation is continued after the platform is at rest. Any possible slackening of the rope sufficient to enable it to free itself from any of the pulleys over which it runs is thereby prevented. At the same time the rotation of the winding drum in this direction raises the counterweights L¹.

What I claim is:—

1. Apparatus for tipping wagons comprising a platform pivoted at one end, a vertically movable hoisting beam pivoted at its upper end to the opposite end of the platform and extending substantially at right angles thereto at the beginning of the lift, a head on the beam capable of engaging with the rear axle of the wagon, guide rod means hinged to the lower end of the beam, its other end being pivoted on a fixed center, a winding drum and means, passing therefrom over pulleys, to raise and lower the beam and platform with means to counterbalance the weight of the platform and wagon, as described.

2. Apparatus for tipping wagons comprising a platform pivoted at one end, a vertically movable hoisting beam pivoted at its upper end to the opposite end of the plat-

form and extending substantially at right angles thereto at the beginning of the lift, a head on the beam capable of engaging with the rear axle of the wagon, guide rod means 35 hinged to the lower end of the beam, its other end being pivoted on a fixed center, a winding drum and means, passing therefrom over pulleys, to raise and lower the beam and platform with means to counterbalance 40 the weight of the platform and wagon, as described.

3. Apparatus for tipping wagons comprising a platform pivoted at one end, a vertically movable hoisting beam pivoted at its 45 upper end to the opposite end of the platform and extending substantially at right angles thereto at the beginning of the lift, a head on the beam capable of engaging with the rear axle of the wagon, guide rod means 50 hinged to the lower end of the beam, its other end being pivoted on a fixed center, a winding drum and means, passing therefrom over pulleys, to raise and lower the beam and platform, extensions on the ends of the winding drum and means passing therefrom 55 to weights counterbalancing the weight of the platform and wagon, as described.

In testimony whereof I have signed my name to this specification.

WILLIAM REID.
